HANDLE MICROPHONE

Ernst Pless, Vienna, Austria, assignor to Akustische U. Kino-Geräte Gesellschaft m.b.H., Vienna, Austria, a firm

Filed May 14, 1963, Ser. No. 280,253

Claims priority, application Austria, May 17, 1962,

A 4,074/62

17 Claims. (Cl. 179—179)

This invention relates to a microphone having a handle which consists of two interfitting and preferably detachably connected parts, one part of which has protruding elements about which the cable connected to the microphone capsule can be wound, according to the prior Patent No. 3,219,765 (application Ser. No. 185,588, filed April 6, 1962).

According to a feature of the invention covered by said prior patent, a holder for the connecting plug is provided between the protruding elements of one part so that all parts of the microphone leading to the outside are accommodated in a protective housing together with the microphone when the same is not used.

The present invention is an improvement of the invention covered by said prior patent.

The embodiments disclosed in said prior patent do not exhaust the possibilities which are inherent in the invention thereof. Special advantages are afforded, e.g., by a development of the handle microphone according to said prior patent, which development will be described hereinafter and is characterized in that the protruding elements of one part have the configuration of an elongated tub, around the outside of which the microphone cable is to be wound, whereas the internal recess defined by said tub serves to accommodate the microphone plug connected to the cable.

According to another feature of the invention, the tub is disposed in the interior of the part which is similar to a box body and can be closed by a shallow part similar to a box cover. The cover is suitably hinged at one end to the other part so that the cover cannot be lost or misplaced.

It has proved highly desirable if the free upper rim of the tub is slightly turned outwardly or provided with a small bead so that this rim and the inside wall of the part similar to a box body and provided with the tub define a slot, the width of which is slightly smaller than the diameter of the microphone cable. In this case, it is not necessary to tension the cable when it is being wound up, but it is sufficient to introduce it under slight pressure into the slot. Because the width of the slot is somewhat less than the diameter of the cable, the latter will not fall out of its holder under any circumstances. A similar arrangement may be provided for the microphone plug, which is accommodated inside the tub.

For this purpose, portions of the tub extending substantially parallel to the longitudinal axis of the tub may be provided on the inside with projections, ribs or the like extending substantially parallel to said axis and restricting the opening through which the plug is inserted into the space provided for its accommodation so that the plug can be inserted only under slight pressure into the internal cavity of the tub. In this case too, the plug cannot readily fall out of its container, because this is prevented by the protruding ribs.

To facilitate the understanding of the invention, it will be described more fully hereinafter with reference to the accompanying drawing.

In the drawing, FIG. 1 is a sectional view taken on line A—A of FIG. 2 and showing the housing of the handle microphone according to the invention.

FIG. 2 is a sectional view taken on line B—B in FIG.

2

1 and showing diagrammatically the complete handle microphone according to the invention.

FIG. 3 is a transverse sectional view taken on line C—C of FIG. 1.

5 The longitudinal sectional view shown in FIG. 1 shows the housing of the microphone to consist essentially of three parts. The right-hand part 1 defines a cavity 10, which is intended for accommodating a microphone capsule, which is diagrammatically indicated at 21 in FIG. 10. 2. The opening 2 exposes the face of the microphone and may be covered with a decorative or protective grid. The left-hand part 3 of the housing is similar to a box body and has in its interior the tub 5. As is also apparent from FIG. 1, the wall of the tub is slightly curved 15 outwardly so that a slot is defined between the inside wall of the box body and the top rim of the tub. As has been described hereinbefore, this slot is so narrow that the microphone cable indicated at 23 in FIG. 2 can be introduced only with slight pressure into the space 6. 20 The partition between the cavity 10 and the space 6 is formed with an open-ended slot 22, shown in FIG. 2, through which the cable extends from the cavity 10 into the space 6. The tub is formed at one end with an open-ended slot 4, through which the cable extends to the 25 microphone plug in the interior of the tub. The microphone plug is indicated at 24 in FIG. 2 and when not used is disposed in the space 7 defined by the tub and is held against falling out by the projections or ribs 9 disposed on those portions of the tub wall 5 which extend substantially parallel to the longitudinal axis of the 30 microphone housing. The projections or ribs 9 are particularly clearly shown in the transverse sectional view shown in FIG. 3. FIG. 2 gives a good impression of the plan form of the housing.

35 For the sake of completeness, reference be made once more to FIG. 1, which shows the third housing part 8 consisting essentially of a shallow box cover, which is suitably hinged at 11 so that it cannot be lost.

The wall of the part 3 is formed with an opening 12, 40 through which the microphone cable extends out in use while the cover is closed. This results in a pleasing appearance of the microphone also in use, without any projecting parts, and in a better protection of the microphone cable and the plug than is afforded by the embodiments described in said prior patent.

45 It will be understood by a person skilled in the art that the material of the tub 5 must be sufficiently resiliently flexible to yield laterally when the plug 24 is inserted into the plug space 7. A material suitable for this purpose is impact polystyrene.

50 What I claim is:

1. A microphone which comprises a microphone capsule, a microphone cable connected at one end to said capsule, a microphone plug connected to the other end of said cable, and a microphone housing defining a cavity 55 accommodating said capsule, said housing further comprising a handle comprising two interfitting parts, one of said parts being formed with a protruding element having an elongated configuration, said protruding element defining on its outside a winding space for said cable and on its inside a plug space for accommodating said plug.

60 2. A microphone as set forth in claim 1, in which said two interfitting parts comprise a body part similar to a box body and a cover part similar to a shallow box cover and said body part being formed with said protruding element.

65 3. A microphone as set forth in claim 2, in which said cover part is hinged at one end to said body part.

70 4. A microphone as set forth in claim 1, in which said protruding element has a laterally outwardly directed free rim and said one part has a wall portion defining with

said free rim a slot which is narrower than the diameter of said cable.

5. A microphone as set forth in claim 1, in which said protruding element has longitudinally extending portions formed on the inside with inwardly directed projections defining an inlet opening to said plug space, said inlet opening being at least partly narrower than said plug space.

6. A microphone as set forth in claim 5, in which said projections extend parallel to said longitudinally extending portions.

7. A microphone as set forth in claim 6, in which said projections consist of ribs.

8. A microphone which comprises a microphone capsule, a microphone cable connected at one end to said capsule, a microphone plug connected to the other end of said cable, and a microphone housing defining a cavity accommodating said capsule, said housing further comprising a handle comprising two interfitting parts, one of said parts being formed with a protruding element having an elongated configuration, said cable being wound around said protruding element, said element defining on its inside a plug space accommodating said plug.

9. A microphone as set forth in claim 8, in which said two interfitting parts comprise a body part similar to a box body and a cover part similar to a shallow box cover and said body part being formed with said protruding element.

10. A microphone as set forth in claim 9, in which said cover part is hinged at one end to said body part.

11. A microphone as set forth in claim 8, in which said protruding element has a laterally outwardly directed free rim and said one part has a wall portion defining with said free rim a slot which is narrower than the diameter of said cable, said protruding element has a longitudinally extending portions formed on the inside with inwardly directed projections defining an inlet opening to said plug space, said inlet opening being at least partly narrower than said plug space.

12. A microphone which comprises a microphone capsule, a microphone cable connected at one end to said capsule, a microphone plug connected to the other end of

said cable, and a microphone housing defining a cavity accommodating said capsule, said housing further comprising a handle comprising two interfitting parts, one of said parts being formed with protruding means around

5 which said cable is wound and which define a space accommodating said plug, said two interfitting parts comprising a body part similar to a box body and a cover part similar to a shallow box cover, said body part being formed with said protruding element, said cover part being hinged at one end to said body part.

10 13. A microphone housing which defines a cavity adapted to accommodate a microphone capsule, said housing further comprising a handle comprising two interfitting parts, one of said parts being formed with a protruding element having an elongated configuration, said protruding element defining on its outside a winding space for a microphone cable and on its inside a plug space for accommodating a microphone plug.

15 14. A microphone housing as set forth in claim 13, in which said two interfitting parts comprise a body part similar to a box body and a cover part similar to a shallow box cover and said body part being formed with said protruding element.

16 15. A microphone housing as set forth in claim 14, in which said cover part is hinged at one end to said body part.

20 16. A microphone housing as set forth in claim 13, in which said protruding element has a laterally outwardly directed free rim and said one part having a wall portion defining with said protruding element said winding space and defining with said free rim a slot which is narrower than said winding space.

25 17. A microphone housing as set forth in claim 13, in which said protruding element has longitudinally extending portions formed on the inside with inwardly directed projections defining an inlet opening to said plug space, said inlet opening being at least partly narrower than said plug space.
